(57) **CLAIM**

The ornamental design for an electronic magnifier, as shown and described.

DESCRIPTION

FIG. 1 is a perspective view of an electronic magnifier showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another perspective view thereof in a collapsed state;

FIG. 10 is an enlarged view of the indicated portion of FIG. 2;

FIG. 11 is an enlarged view of the indicated portion of FIG. 10; and,

FIG. 12 is an enlarged view of the indicated portion of FIG. 4.

As shown in FIG. 2, the electronic magnifier displays an image frame of an object photographed on a monitor (A) installed in front of a main body by electronically magnifying through a camera (B) provided on the upper side of the main body. The design can be folded and stored as shown in FIG. 9.

The broken lines illustrate portions of the electronic magnifier and form no part of the claimed design.
